[57] **CLAIM**

The ornamental design for a head for a differential pressure measuring and transmitting housing, substantially as shown and described.

DESCRIPTION

FIG. 1 is a perspective view of a head for a differential pressure measuring and transmitting housing embodying my new design;

FIG. 2 is a rear elevational view thereof;

FIG. 3 is a front elevational view thereof;

FIG. 4 is a right elevational side view thereof;

FIG. 5 is a left side elevational view thereof;

FIG. 6 is a top plan view thereof; and

FIG. 7 is a bottom plan view thereof.

The broken lines are shown for illustrative purposes only and form no part of the claimed design.
